ATTORNEY

UNITED STATES PATENT OFFICE.

JEREMIAH J. KING, OF NEW YORK, N. Y.

MAT-LOCK AND SCRAPER.

SPECIFICATION forming part of Letters Patent No. 269,795, dated December 26, 1882.

Application filed June 7, 1882. (No model.)

To all whom it may concern:

Be it known that I, JEREMIAH J. KING, a citizen of the United States, residing at New York, in the county and State of New York, have 5 invented new and useful Improvements in Mat-Locks and Scrapers, of which the following is a specification.

This invention relates to that class of mat-locking devices for which I filed an application for Letters Patent on or about the 17th day of May, 1882; and it consists in providing one of the jaws of the link with a foot-scraper, as hereinafter described, so that when the link is fastened to a mat the scraper is thereby 15 held in a position for use.

This invention is illustrated in the accompanying drawings, in which Figure 1 represents a side view, partly in section, showing the link applied to a mat. Fig. 2 is a plan or 20 top view.

Similar letters indicate corresponding parts.

The letter A designates the mat, and B the link, serving to receive a chain for locking the mat to the desired part of a building. This 25 link is composed of two jaws, D E, which are connected together at one end by a pivot, f, or other suitable means, and at the other end by a post, g, which is a fixture of one jaw, and receives in it a screw, h, countersunk in the 30 other jaw. The screw h, however, can be omitted, in which case the post g is riveted to the appropriate jaw. One of the jaws, moreover, is provided with a tooth, i, which passes through the mat, together with the post g, and 35 serves to hold the link against turning on the post.

The letter J indicates a foot-scraper combined with the jaw D of the link. This scraper consists of a blade of sheet metal or other suitable material, and extends nearly 40 the entire length of the link, it being secured to the back of the jaw D approximately at a right angle thereto, and hence if the jaw D is brought above the mat, as shown, in fastening the link thereto the scraper is thereby held 45 upright in position for use, thus forming a highly useful auxiliary to the mat. In the example shown the scraper is held to the jaw D by being riveted to lugs o thereon; but this purpose can be accomplished in various other 50 ways, which will readily suggest themselves to a skilled mechanic.

The object of using the screw h is to allow the link to be detached from the mat when the latter is worn out, and to be applied to a new 55 mat.

What I claim as new, and desire to secure by Letters Patent, is—

1. The link herein described, having one of its jaws provided with a foot-scraper adapted 60 to take a position for use when the link is applied to a mat.

2. The combination of the link-jaws D E, the post g, tooth i, and scraper J, substantially as and for the purpose described. 65

In testimony whereof I have hereunto set my hand and seal in the presence of two subscribing witnesses.

JEREMIAH J. KING. [L. S.]
